UNITED STATES PATENT OFFICE.

ALBERT S. SMELSER, OF ANDERSON, INDIANA.

WIRE-WIPPING MACHINE.

1,073,297.

Specification of Letters Patent.

Patented Sept. 16, 1913.

Application filed June 17, 1912. Serial No. 704,161.

To all whom it may concern:

Be it known that I, ALBERT S. SMELSER, a citizen of the United States, residing at Anderson, in the county of Madison and State 5 of Indiana, have invented certain new and useful Improvements in Wire-Wipping Machines; and I do declare the following to be a full, clear, and exact description of the invention, such as will enable others skilled 10 in the art to which it appertains to make and use the same.

This invention relates to improvements in wire wiping machines.

One object of the invention is to provide 15 a wire wiping machine having an improved means for automatically raising and lowering the wiping mechanism to permit knots, joints or other obstructions in the wire to readily pass without tearing or pulling out 20 the wiping material from its holders or breaking the wire.

Another object of the invention is to provide 25 a machine of this character which will be simple, strong, and durable in construction, efficient and reliable in operation and well adapted to the purpose for which it is 30 designed.

With these and other objects in view, the 35 invention consists of certain novel features 40 of construction, and the combination and arrangement of parts as will be more fully described and claimed.

In the accompanying drawings; Figure 1 is a front view of my improved wire wiping 45 machine, parts being broken away; Fig. 2 is an enlarged front view partly in section of a portion of the machine; Fig. 3 is a vertical cross sectional view taken on the line 3—3 of Fig. 2 and showing the parts in an 50 operative position; Fig. 4 is a view similar to Fig. 3 taken on a different line and showing the parts raised or in an inoperative position to permit the passage of an obstruction in the wire being wiped; Fig. 5 is a vertical longitudinal section of a portion of the 55 machine taken on the line 5—5 of Fig. 3; Fig. 6 is a horizontal sectional view of a portion of the machine taken on the line 6—6 of Fig. 3; Fig. 7 is a similar view taken on the line 7—7 of Fig. 3; Fig. 8 is a detail side view of one of the supporting levers for supporting the upper holding mechanism for 60 the wiping material in elevated position until the knot or obstruction in the wire has 65 passed the wipers. Fig. 9 is a rear view of the same; Fig. 10 is a side view of one of

the tripping members for raising the upper holding mechanism for the wiping material; Fig. 11 is a front view of the same.

My improved wire wiping machine comprises lower and upper base or magazine supporting plates 1 and 2 which are designed to receive and support the upper and lower magazines or holders for the asbestos wiping material as will be more fully described. The 60 base plate 1 may be secured to any suitable support (not shown) and the upper base plate 2 is secured to and spaced a suitable distance from the lower plate 1 by a series of bolts 3, the upper ends of which are 65 threaded and screwed into threaded sockets in the lower side of the upper plate 2, while the lower ends of the bolts pass through bolt holes in the lower plate 1 and have their extremities threaded to receive nuts 4. On 70 the bolts 3 between the plates 1 and 2 are arranged spacing sleeves 5 by means of which the plates 1 and 2 are spaced a suitable distance apart. The lower base plate 75 1 has on its upper side a longitudinally disposed rib or offset 6 whereby the plate at this point is increased in thickness. The upper plate 2 is of greater thickness along its central portion and the thinner front portion of the plate is extended from the lower 80 portion thereof, while the thinner rear portion of the plate is extended from the upper part of the central portion thereby forming 85 shoulders 7 and 8 on the front and rear edges of the thicker central portion of the 90 plate as shown.

In the central portion of the lower plate 1 and its rib 6 are a series of vertically disposed passages 9 the lower ends of which are enlarged and threaded to form slightly 95 tapered sockets 10 with which are engaged the reduced threaded upper ends of a series of lower magazines or holders 11 for the lower wipers 12, said wipers being in the form of asbestos, wool or similar material 100 which is placed in the magazines or holders 11 and in the passages 9 in the plates 1 above the magazines. The material forming the wipers 12 is forced or fed upwardly and projected a suitable distance above the 105 magazines 11 in the passages 9 by a plunger 13, the stem or shank 14 of which has a threaded engagement with a plug 15 which is screwed into the lower end of the magazine 11 as shown. In the rib 6 of the lower 110 plate 1 and intersecting the center of the passages 9 are a series of transversely dis-

posed wire guiding grooves 16 through which the wire passes when wiped as will be hereinafter more fully described.

In the upper base plate 2 immediately above the passages 9 in the lower plate are a series of vertically disposed guide passages 17 in which are slidably mounted the lower ends of a series of upper magazines or holders 18 for the upper wipers 19. The magazines or holders 18 are preferably in the form of cylindrical tubes of sufficient length, said tubes having their lower ends slidably engaged with the passages 17 in the plate 2 and having their upper ends slidably engaged with the passages 20 in an upper guiding and supporting plate 21 which is secured to the plate 2 by series of bolts 22 and is spaced a suitable distance from the lower plate by tubes or sleeves 23 arranged on the bolts 22 as shown. The bolts 22 have their lower ends threaded and screwed into threaded sockets 24 in the plate 2, while their upper ends pass through apertures in the plate 21 and have their extremities reduced and threaded to receive clamping nuts 25 which are screwed thereon and into engagement with the upper sides of the plates 21.

The lower ends of the magazines or tubes 18 normally terminate close to or in engagement with the upper side of the rib 6 of the lower plate 1, and the asbestos or other material in the tubes or magazines which forms the upper wiper 19 is fed downwardly and held in engagement with the lower wipers by a series of upper plungers 26, the stems 27 of which have a threaded engagement with plugs 28 screwed in the upper ends of the tubes or magazines 18 as shown. By thus constructing and arranging the upper and lower magazines or wiper holders and wipers, it will be seen that the wires when drawn through the grooves 16 in the rib 6 of the lower plate and between the engaging ends of the wipers that the surplus galvanizing material or coating which is applied to the wires will be smoothly and evenly wiped off the wires.

The upper magazines or holders are yieldingly held down in position to engage the wiping material therein with the wiping material in the lower holder by coiled springs 29 arranged on the tubes or magazines between the upper plate 21 and collars 30 which are clamped to the tubes or magazines a suitable distance above the plate 2 as shown. The collars 30 have on one side pairs of apertured lugs 31 the purpose of which will be hereinafter described. In order to automatically lift or raise the tubes or upper magazines 18 at the proper time to permit the passage of knots, twists or other obstructions in the wires, so that such knots or obstructions will not catch the lower ends of the magazine or the wire

wiping material therein and thus break the wire or pull the wiping material out, I provide a suitable magazine lifting mechanism comprising a series of segmental plates or levers 32 which are engaged with notches 33 formed in the forwardly projecting offset front portion of the plate 2 and which are pivotally engaged with pins or bolts 34 arranged in recessed supporting blocks 35 one of which is secured to the upper side of the forwardly projecting portion of the plate 2 over each of the notches 33 formed therein. The blocks 35 are preferably secured to the outer portions of the plate 2 by screws or similar fastening devices 36. Secured to the squared outer or forward ends of the plates or levers 32 are forked tripping plates 37 the forked or bifurcated lower ends of which project below the levers 32 and are adapted to receive the wires which are drawn therethrough after leaving the galvanizing tanks and before passing between the wipers.

The inner ends of the plates or levers 32 have pivotally connected thereto the lower ends of a series of links 38 the upper ends of which are pivotally connected to pairs of apertured lugs 39 on the forward ends of collars 40 which are engaged with the magazines or tubes 18 below the collars 30 and which engage and rest on the upper side of the central portion of the plate 2 and form supports for the collars 30 engaged with the magazine tubes 18 above the collars 40 as hereinbefore described. By thus arranging the magazine lifting mechanism as herein shown and described it will be seen that when a knot, twist or other obstruction in the wires comes into engagement with the forked lower end of the trip plates 37, said plates together with the levers 32 will be swung inwardly and then upwardly thereby causing the links 38 to lift the collars 40 which being engaged with the collars 30 will lift the latter and the magazine tubes to which they are clamped, thereby permitting the knot or obstruction in the wire to pass freely between the raised lower end of the upper magazine and the lower magazine without tearing or pulling out the asbestos wire wiping filling of the magazines.

In order to automatically catch and support or hold the upper tubes or magazines in an elevated position while the obstruction in the wire is passing through the machine, I provide a series of supporting catches in the form of levers 41 one of which is pivotally mounted in the apertured lugs 31 of each of the collars 30. In the rear edges of the supporting levers 41 are notches 42. On the lower ends of the levers 41 are right angularly formed depending trip fingers 43.

Arranged on and secured to the upper side of the rearwardly projecting portion of the plate 2 are a series of magazine sup-

porting bars 44 against which the inner edges of the levers 41 bear when the upper magazines or wiping holders are raised and with which the notches 42 engage when the magazines or holders have been raised whereby the latter are held in an elevated position until the knot or obstruction in the wire passes between the wipers. The lower ends of the fingers 43 of the levers 41 are forked or bifurcated as at 45 and through said forked ends of the levers the wires pass from the wipers. By thus arranging the supporting levers 41 it will be seen that after the magazines have been raised to permit the knots or obstructions in the wire to pass the wipers the knots or obstructions when coming into engagement with the bifurcated lower ends of the trip fingers 43 of the levers will swing the latter outwardly thereby disengaging the notch 42 from the bars 44 which will permit the springs 29 to again force the magazines 18 downwardly to engage the wipers carried thereby with the wipers in the lower magazine, thus again bringing said wipers into operative position for wiping the surplus material from the wires.

By constructing and arranging my improved wire wiping machine as herein shown and described it will be seen that the wipers will be automatically separated to permit the passage of any knots, twists or obstructions which would interfere with the free passage of the wire between the wipers, thus obviating the danger of breaking the wire or tearing out the wiping material.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. In a wire wiping machine, the combination with upper and lower supporting plates, lower magazines secured to said lower plate, upper magazines slidably mounted in said upper plate, a guiding plate spaced above said upper supporting plate, collars secured to said upper magazines, springs between said collars and upper guiding plate, and wiping material in said magazines; of a series of pivotally supported levers, links connecting them with the collars on said magazines, forked tripping plates on said levers and adapted to be engaged by obstructions in the wires, a series of other levers each pivoted to one of said collars and having a notch in its body and a finger in its lower end for the purpose
2. In a wire wiping machine, the combination with upright guides, a lower magazine seated in the lower guide, an upper magazine movably mounted in the upper guide, wiping material within said magazines, and means for feeding it toward the wire being treated; of a framework carrying said guides, a supporting bar across the framework, levers pivoted at their upper extremities to said upper magazines and each having a notch in its body adapted to rest over said bar, its lower end being forked and passing astride the wire being treated, a forked trip finger standing astride said wire forward of the magazine, and connections between this finger and the upper magazine whereby the latter is raised by a knot in the wire.
3. In a wire wiping machine, upper and lower magazine supporting plates, means to connect and space said plates a suitable distance apart, lower wiper holding magazines secured to said lower plate, upper wiper holding magazines slidably mounted in said upper plate, a magazine guiding plate spaced above and secured to said upper magazine supporting plate to receive and guide the upper ends of said upper magazines, upper and lower collars secured to said upper magazines, springs arranged between said upper collars and said upper guiding plate whereby the upper magazines are yieldingly held in operative position, wiping material arranged in said magazines and held thereby in position to engage the wires drawn through the machine, an upper magazine lifting mechanism comprising a series of pivotally supported levers connected at one end with the lower collars on said magazines, forked tripping plates secured to the opposite ends of said levers and adapted to be engaged by obstructions in the wires whereby the levers are rocked and said upper magazines thereby raised, means to support said magazines in a raised position while the obstructions are passing the magazines, and means whereby said supporting means is tripped by the obstructions in the wires to permit the magazines to lower.
4. In a wire wiping machine, a lower magazine supporting plate, and an upper magazine supporting plate having therein a series of notches, a series of lower wiper holding magazines fixed in said lower supporting plate, a series of upper wiper holding magazines slidably mounted in said upper plate, wire wiping material arranged in said magazines, upper and lower collars secured to said upper magazines, springs to hold the latter in operative position, an upper magazine lifting mechanism comprising a series of supporting blocks secured to said

set forth, and a supporting bar carried by the lower plate over which said notch rests.

2. In a wire wiping machine, the combination with upright guides, a lower magazine seated in the lower guide, an upper magazine movably mounted in the upper guide, wiping material within said magazines, and means for feeding it toward the wire being treated; of a framework carrying said guides, a supporting bar across the framework, levers pivoted at their upper extremities to said upper magazines and each having a notch in its body adapted to rest over said bar, its lower end being forked and passing astride the wire being treated, a forked trip finger standing astride said wire forward of the magazine, and connections between this finger and the upper magazine whereby the latter is raised by a knot in the wire.

3. In a wire wiping machine, upper and lower magazine supporting plates, means to connect and space said plates a suitable distance apart, lower wiper holding magazines secured to said lower plate, upper wiper holding magazines slidably mounted in said upper plate, a magazine guiding plate spaced above and secured to said upper magazine supporting plate to receive and guide the upper ends of said upper magazines, upper and lower collars secured to said upper magazines, springs arranged between said upper collars and said upper guiding plate whereby the upper magazines are yieldingly held in operative position, wiping material arranged in said magazines and held thereby in position to engage the wires drawn through the machine, an upper magazine lifting mechanism comprising a series of pivotally supported levers connected at one end with the lower collars on said magazines, forked tripping plates secured to the opposite ends of said levers and adapted to be engaged by obstructions in the wires whereby the levers are rocked and said upper magazines thereby raised, means to support said magazines in a raised position while the obstructions are passing the magazines, and means whereby said supporting means is tripped by the obstructions in the wires to permit the magazines to lower.

4. In a wire wiping machine, a lower magazine supporting plate, and an upper magazine supporting plate having therein a series of notches, a series of lower wiper holding magazines fixed in said lower supporting plate, a series of upper wiper holding magazines slidably mounted in said upper plate, wire wiping material arranged in said magazines, upper and lower collars secured to said upper magazines, springs to hold the latter in operative position, an upper magazine lifting mechanism comprising a series of supporting blocks secured to said

upper supporting plate, lifting levers pivoted in said blocks and adapted to engage the notches in said plate, links to connect one end of said levers to the upper collars of the magazines, forked tripping plates secured to the opposite ends of said levers to receive the wires, whereby obstructions in the latter will engage said plates and trip said levers, thereby raising the upper magazines, magazine supporting levers pivotally secured to said upper collars and having therein notches, supporting bars on said upper magazine supporting plate adapted to be engaged by the notches in said levers whereby the magazines are supported in an

elevated position when raised by said lifting mechanism, and bifurcated trip fingers on said supporting levers adapted to be engaged by the obstructions in the wire whereby said levers are tripped to permit the 20 springs on said magazines to lower the latter.

In testimony whereof I have hereunto set my hand in presence of two subscribing witnesses.

ALBERT S. SMELSER.

Witnesses:

IRA V. SMELSER,
JACOB G. HOFFNER.
